(57) **CLAIM**

The ornamental design for a headgear for a nasal mask as shown and described.

DESCRIPTION

FIG. 1 is a top, front and left side perspective view of a first embodiment of a headgear for a nasal mask showing our new design;

FIG. 2 is a bottom, rear and right side perspective view of FIG. 1;

FIG. 3 is a front elevational view of FIG. 1;

FIG. 4 is a rear elevational view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a top, front and left side perspective view of a second embodiment of the headgear for a nasal mask;

FIG. 10 is a bottom, rear and right side perspective view of FIG. 9;

FIG. 11 is a front elevational view of FIG. 9;

FIG. 12 is a rear elevational view of FIG. 9;

FIG. 13 is a left side view of FIG. 9;

FIG. 14 is a right side view of FIG. 9;

FIG. 15 is a top plan view of FIG. 9; and,

FIG. 16 is a bottom plan view of FIG. 9.
